RATCHET MECHANISM

Walter B. Claus, Van Nuys, Calif., assignor, by
mesne assignments, to Howe & Fant, Inc.,
South Norwalk, Conn., a corporation of Dela-
ware

Application October 29, 1945, Serial No. 625,257

4 Claims. (Cl. 74—142)

1

This invention has to do with a ratchet mechanism which is capable of selectively moving a driven member in either of two opposite directions, depending upon the direction of initial actuation of the mechanism. The invention is especially useful and has been designed particularly for a receiver in a telemetering system; and, although the invention is not limited to that particular use, it will be described in its present preferred and illustrative form as for that use.

In telemetering systems such as that set out in the application of Gabriel M. Giannini, Ser. 597,459, filed June 4, 1945, and entitled Telemetric system, now Patent No. 2,471,947, a transmitter instrument generates and delivers a series of spaced electrical pulses of a sign dependent upon the direction of actuation of the transmitter. The series of pulses is received by a receiver instrument, whose function is to move a driven member step by step in one direction or the opposite direction, depending upon the sign of the received pulses. The receiver, in effect, algebraically adds the received pulses and operates its driven member accordingly. That driven member may actuate an indicator, or it may actuate a device or mechanism which is remotely controlled from the transmitter.

The general purpose and object of the present invention is to provide a two-way ratchet mechanism, especially adapted for use in a telemetric receiver, and which is capable of dependable actuation by polarized electrical impulses of small magnitude, short duration and rapid succession. The present preferred forms of the invention will be explained in illustrative detail in the following detailed description, reference being had to the accompanying drawings in which

Fig. 1 is a diagrammatic perspective illustrating essentials of my invention;

Fig. 2 is a plan section of a developed form of the invention, taken as indicated by line 2—2 on Fig. 3;

Fig. 3 is a central vertical section taken as indicated by line 3—3 on Fig. 2, with certain parts in elevation;

Fig. 4 is a fragmentary section on line 4—4 of Fig. 3; and

Fig. 5 is an elevation of the mechanism, the view being taken in an aspect from the right on Fig. 3.

Figs. 2 and 3 are to a scale approximately five times the linear dimensions of an actual device, and Figs. 4 and 5 are on a smaller scale.

Referring first to Fig. 1, an actuating shaft

2

is shown at 10, carrying a coil 11 which is located in a magnetic field diagrammatically indicated by the arrows 12. The relation of the coil to the magnetic field is such that current flowing through the coil in one direction will cause angular movement of the shaft in a predetermined direction of rotation, while current flowing in the opposite direction through the coil will cause rotation of the shaft through an angle in the opposite direction. The electro-magnetic means for rotating shaft 10 in opposite directions by electrical pulses of opposite signs may be of a nature different from that of the moving coil type which I here describe. For instance, in the mentioned Giannini application a receiver is shown as actuated by a driver which has a moving magnet. I make no claim herein to either type of driver, in and of itself.

In my ratchet mechanism as here illustrated, a double ended arm 13 is fixed on shaft 10, and a pawl 14 is pivoted to each of the two ends of the arm. Pawls 14 are shown here as essentially straight rods or bars and normally in substantial parallelism with each other. As shaft 10 and arm 13 swing in either clockwise or counter-clockwise direction one pawl 14 moves upwardly in Fig. 1, and the other pawl moves downwardly. The two pawls are guided by suitable guide stops, here shown as stationary pins 15, against which the pawls are pressed by two springs 16.

Fig. 1 illustrates the normal position of the mechanism, which it assumes when at rest. Arm 13 and pawls 14, and actuating coil 11 are held in this normal position by a pair of centering springs 17 which are shown in Fig. 1 as yieldingly holding a pin 18 between their free ends. Pin 18 is set in arm 13, and in the normal centered position, the springs may engage shaft 10 as well as pin 18. Such an arrangement serves to reduce elastic resonant vibration of the parts about the centered normal position. From Fig. 1 it will be noted that the whole mechanism in its central normal position is symmetrically arranged with reference to a vertical plane passing through the axis of shaft 10. Ratchet wheel 20 is mounted on an axis 21 located in that plane and parallel to the axis of shaft 10. Thus, the mechanism as illustrated in Fig. 1, is symmetric with relation to a plane determined by axis 21 of ratchet 20 and the axis of shaft 10.

As shown in Fig. 1, pawls 14 project from arm 13 toward the ratchet 20, and in the normal position the free ends 14a of the pawls lie under two teeth of the ratchet, but preferably not in

immediate contact with them. In the preferred form of the mechanism as here shown, the two particular teeth 20a are not diametrically opposed to each other, but are separated by a chordal distance (in Fig. 1 this chordal distance is horizontal) which is substantially less than the diameter of the ratchet wheel. The straight two pawls 14 are so spaced and guided by pins 15 that the horizontal distance between their two free ends is also less than the diameter of the ratchet wheel. That horizontal spacing of the two pawls is such that their upper free ends, lying under the two particular teeth 20a, clear the next two teeth 20b which lie just below the two teeth 20a. In other words, using pawls which are simple straight bars, those pawls extend and have their guided movements along lines which are non-tangential to the toothed periphery of the ratchet wheel. It is not necessary that the pawls be in substantial parallelism; but that is a simple and effective arrangement of the two straight pawls.

The ratchet wheel is yieldingly held in the relative normal position shown in Fig. 1 by a spring detent, such as that illustrated at 25 engaging a space between teeth of the ratchet.

If we now assume that shaft 10 and arm 13 are swung in a clockwise direction, then the left hand ratchet 14a will move up into engagement with the left hand tooth 20a, and further movement will then move ratchet 20 in a clockwise direction. In its preferred form the mechanism is designed to move ratchet 20 through only the distance of one tooth on each actuation, and stops are preferably provided as will be later explained, to limit the swinging of arm 13. During the upward movement of the left hand pawl, the right hand pawl 14 moves downwardly through a distance substantially equal to the distance of the upward movement of the left hand pawl; and in moving downwardly, the right hand pawl moves away from the ratchet, so that the right hand tooth 20a will clear the end of the right hand pawl as the ratchet wheel rotates. During the upward movement of the left hand pawl, the left hand tooth 20b may come into engagement with that pawl; but if it does so, it merely pushes that pawl slightly outwardly against the light pressure of spring 16, but does not push that pawl outwardly far enough to move its end out of engagement with the left hand tooth 20a. On return movement of the pawls to normal position, the left hand pawl drags down over left hand tooth 20b and then is sprung in under it; the right hand pawl moves upwardly, guided by pin 15 to clear the right hand tooth 20a which has now taken the position previously occupied by tooth 20b.

On cessation of the force which has swung shaft 10 clockwise, the centering springs 17 immediately return the pawl mechanism to normal position, and leaving ratchet wheel 20 in its advanced position. The whole mechanism then again stands in the position illustrated in Fig. 1, ready for a subsequent actuation. If that subsequent actuation is in an opposite direction, swinging shaft 10 counter-clockwise in Fig. 1, the right hand pawl 14 then acts to engage the right hand teeth 20a to rotate ratchet 20 through one step in a counterclockwise direction.

The whole mechanism illustrated in Fig. 1 is capable of being designed into a very small instrument and with its moving parts having very low inertias. The instrument is therefore capable of rapid successions of actuation by very

small pulses of short duration. Figs. 2 and following show a preferred design development of such an instrument.

In Figs. 2 and following the actuating coil is shown at 50, mounted on a shaft 51, which is journaled at its upper and lower ends in bearings in a frame plate 52 and in a bracket member 53 which forms a part of the framing of the instrument. I may remark that, as shown in Figs. 2 to 5, the instrument is shown with coil shaft 51 in a vertical position with a ratchet mechanism in a horizontal plane, merely for convenience of illustration. The instrument in use may assume any relative orientation. Coil 50 rotates in a gap between two magnetic pole pieces 55 and a central core 56, core 56 being mounted on the bracket member 53. Pole pieces 55 form the poles of a magnetic circuit which includes two permanent magnets 57 and a yoke 58. The coil normally stands in the relative position shown in Fig. 4 when the ratchet mechanism is in its normal inactive position such as shown in Fig. 2. Connections to the coil are made in any suitable manner, as through the spiral connectors 59 shown in the drawings.

As shown in Figs. 2 and 3, the pawl carrying arm 60 is mounted on shaft 51 above coil 50. The upper face of arm 60 is provided with a central flat block 61 which is yieldingly confined between the two centering springs 62, whose fixed ends are set in an upper extension 53a of frame member 53. The elastic pressures of these springs on block 61 may be suitably adjusted by the adjustment screws shown at 63 in Figs. 2 and 3. Suitable stops for the swinging motion of pawl arm 60 are provided by the stop pins shown at 64 in Figs. 2 and 3. These stop pins may be conveniently mounted for adjustment as shown in the drawings, being eccentric projections from screws 65 which are rotatably set in upper frame plate 52.

The two ratchet pawls are shown at 70, pivoted to the ends of arm 60 and extending their free ends, in substantial parallelism, toward the toothed ratchet wheel 71, which is mounted on shaft 72, that shaft being shown as journaled in bearings in upper frame plate 52 and in a lower frame plate 73 which also forms a part of the framing of the instrument. As here shown, shaft 72 may also carry a pinion 74 meshing with a larger gear 75 on a shaft 76. An extension 77 of that shaft may, for instance, carry an indicating pointer which moves over a calibrated dial. Or shaft 77 may be connected to any instrument, device or mechanism which is to be remotely controlled.

Adjustable guides for pawl 70 are shown in the form of pins 80 which are eccentrically carried by rotatable screws 81 set in the upper frame plate 52. Springs 83 lightly press pawls 70 against guide pins 80. The fixed ends of those springs are secured at 84 to a part of the stationary frame; and pressure exerted by the springs may be adjusted by eccentric pins 85 which are mounted on rotatable screws 86 set in upper plate 52. Extensions 83a of springs 83 serve as detents to engage between teeth of ratchet gear 71 to hold it releasably in normal position.

The general relationship of the several parts, and their functions, is the same as is shown in Fig. 1 and as has been described for that figure. In the specific design of Fig. 2 it will be noted that the parts of the ratchet mechanism, in normal inactive positions, are symmetrically arranged with reference to a plane determined by

the axes of shafts 51 and 72. The two pawls 70 lie and move in substantial parallelism, and their ends lie adjacent two teeth 71a of ratchet wheel 71 and normally clear the two teeth 71b.

I claim:

1. A ratchet mechanism comprising a rotatable toothed wheel, a pawl carrying arm pivoted centrally on an axis parallel to the axis of rotation of the wheel and located to one side of the wheel, a pair of pawls pivoted to the opposite ends of the arm, the pawls extending parallel and substantially tangent to the wheel and with their free ends lying close to respective teeth on the wheel, when the arm is at rest and lies normal to a line connecting the axes of the wheel and arm, and means engaging the pawls between their ends and guiding the pawls to move non-tangentially to the wheel, as the arm is swung on its pivot.

2. A ratchet mechanism comprising a rotatable toothed wheel, a pawl carrying arm pivoted centrally on an axis parallel to the axis of rotation of the wheel and located to one side of the wheel, a pair of pawls pivoted to the opposite ends of the arm, the pawls extending parallel and substantially tangent to the wheel and with their free ends lying close to respective teeth on the wheel, when the arm is at rest and lies normal to a line connecting the axes of the wheel and arm, and means engaging the pawls between their ends and guiding the pawls to move non-tangentially to the wheel, as the arm is swung on its pivot, said means including guide stops limiting inward movement of the pawls toward one another and yielding means pressing the pawls against the stops.

3. A ratchet mechanism comprising a rotatable toothed wheel, a pawl carrying arm pivoted centrally on an axis parallel to the axis of rotation

of the wheel and located to one side of the wheel, a pair of pawls having the form of substantially straight bars pivoted to the opposite ends of the arm, the pawls extending parallel and substantially tangent to the wheel and with their free ends lying close to respective teeth on the wheel, when the arm is at rest and lies normal to a line connecting the axes of the wheel and arm, and means engaging the pawls between their ends and guiding the pawls to move non-tangentially to the wheel as the arm is swung on its pivot.

4. A telemetric receiver mechanism comprising a ratchet mechanism which includes a rotatable toothed wheel, a pawl carrying arm pivoted centrally on an axis parallel to the axis of rotation of the wheel and located to one side of the wheel, a pair of pawls pivoted to the opposite ends of the arm, the pawls extending parallel and substantially tangent to the wheel and with their free ends lying close to respective teeth on the wheel, when the arm is at rest and lies normal to a line connecting the axes of the wheel and arm, and means engaging the pawls between their ends and guiding the pawls to move non-tangentially to the wheel, as the arm is swung on its pivot, and electro-magnetic means adapted selectively to swing the pawl arm in either direction from its normal position.
